UNITED STATES PATENT OFFICE.

JOHN ENDRES, OF SOUTH MILWAUKEE, WISCONSIN.

WINDOW.

SPECIFICATION forming part of Letters Patent No. 549,909, dated November 19, 1895.

Application filed August 12, 1895. Serial No. 558,965. (No model.)

To all whom it may concern:

Be it known that I, JOHN ENDRES, a citizen of the United States, and a resident of South Milwaukee, in the county of Milwaukee and 5 State of Wisconsin, have invented certain new and useful Improvements in Windows; and I do hereby declare that the following is a full, clear, and exact description thereof.

In a previous application, Serial No. 540,632, filed March 5, 1895, I show and describe both parting-stops in a window-frame as having simultaneous lateral adjustment; and my present invention has for its object to provide window-frames each of which has a rigid parting-stop and a laterally-adjustable parting-stop, whereby I economize in the production of such frames and at the same time insure a means for locking a window-sash in various positions of its possible adjustment and at the same time prevent rattle of said sash. Hence 15 said invention consists in certain peculiarities of construction and combination of parts hereinafter set forth with reference to the accompanying drawings and subsequently 20 claimed.

In the drawings, Figure 1 represents a window-frame embodying my improvements as viewed on the plane indicated by line 1 1 in Fig. 2; Fig. 2, a horizontal section taken on line 2 2 of Fig. 1; Fig. 3, a detail view on the plane indicated by line 3 3 in Fig. 2, a part of the framing being broken away to permit illustration of a stay-strip embodied in my improvements; Fig. 4, a detail horizontal section on line 4 4 of Fig. 1; Fig. 5, a detail view on the plane indicated by line 5 5 in Fig. 2, and Fig. 6 a perspective view of a guide and bearing-bracket also embodied in my improvements.

Referring by letter to the drawings, A represents a window-frame of ordinary construction, except in the matter of a parting-stop and other details hereinafter specified. Both parting-stops B C of the window-frame are 45 beveled in opposition to correspondingly beveled edges of the sash D, and only the parting-stop C is movable laterally in the adjacent jamb of said frame in order that a clamping action may be had against said sash to 50 lock the latter in various positions of its possible vertical adjustment, the other parting-stop B being rigidly secured in position.

The movable parting-stop C is provided with oblique wings b, that engage corresponding notches c in a staff E, that is loose in the 55 adjacent jamb of the window-frame, and by vertical movement of the staff the lateral adjustment of said stop is effected because of the engagement of the stop-wings with the staff-notches.

In order to vertically adjust the staff E, I provide the same with a plate F, having a lug d in dovetail or other suitable slip connection with a rack-bar G, that is guided in a bracket H, fast on a block I in the window-frame, a pinion J, journaled in the bracket, being meshed with the teeth of said bar and connected to a rod K, that extends through a socket-plate L, fast upon the inside casing of said window-frame. The rod K is preferably 65 square, especially so much thereof as extends through the socket-plate L, and a crank-key 70 M enters said socket-plate to engage said rod, the connection between the key and rod being preferably such that the former may be 75 readily disengaged.

The bracket H is best shown in Fig. 6, and the face-lug e, together with the right-angle edge-lug f, constituting parts of said bracket, constitute the guides for the rack-bar G, above 80 specified. The bracket is further provided with a slot g and hook-lug h, that serve as bearings for the journals of pinion J, and the rod K being detached from said pinion the latter may be readily disengaged from said 85 bracket after removal of said rack, these parts being accessible through the usual opening to the weight-pocket in which they are contained.

In order to prevent the movable parting-stop and the parallel staff from falling out of place when the window-sash is removed, I provide the adjacent jamb of the window-frame with a chamber i for a horizontal strip j, that is held in place by a screw k to have 95 one end thereof engage a lengthwise notch m in said staff, the screw being concealed by one of the inner sash-stops n, as clearly illustrated in Fig. 2. By loosening the screw k the strip j may be pushed back in the chamber i to 100 clear the notch m in the vertically-adjustable staff, and thus permit removal of this staff and the laterally-adjustable parting-stop.

The travel of the rack-bar G is limited in

opposite directions by means of stops *p* on the window-frame, and as a matter of preference the parting-stop *C* has its wings *b* alternately on opposite sides, the notches *c* in the staff *E* being correspondingly disposed to thus avoid any material weakening of said stop and staff.

While I have shown the oblique stop-wings and staff-notches, it is possible to substitute other means for insuring lateral adjustment 10 of parting-stop *C* when the rack-and-pinion mechanism is actuated, and in other matters of detail certain variations are possible within the scope of my invention.

Having now fully described my invention, 15 what I claim as new, and desire to secure by Letters Patent, is—

1. A window-frame provided with a bracket presenting guide-lugs and journal-bearings, a rack-bar opposing the lugs, a pinion mounted 20 in the bearings to mesh with the rack-bar, a staff connected to said rack-bar, a loose parting-stop, and suitable means for effecting lateral adjustment of the parting-stop coincident with longitudinal movement of the 25 staff.
2. A window-frame provided with a loose parting-stop, a staff in such connection with the stop as to effect lateral adjustment of the same coincident with longitudinal movement

of itself, and a stay in the window-frame engageable with a lengthwise notch in said staff. 30

3. A window-frame provided with a loose parting-stop having oblique wings alternately on opposite sides, a staff having correspondingly disposed notches engaging the wings, 35 and suitable means for effecting longitudinal movement of the staff.

4. A window-frame having a rigid parting-stop and a movable parting-stop, oblique wings extended from the movable stop, a reciprocal staff having oblique notches engaged by said wings, a plate secured to the staff and provided with a lug, a rack-bar detachably connected to the lug, suitable guides for the rack-bar, a pinion in mesh with said 40 rack-bar, a rod extending from the pinion through the window-frame casing, and a crank-key engageable with the outer end of the rod.

In testimony that I claim the foregoing I 50 have hereunto set my hand, at Milwaukee, in the county of Milwaukee and State of Wisconsin, in the presence of two witnesses.

JOHN ENDRES.
